US00D850534S

(12) **United States Design Patent** (10) Patent No.: **US D850,534 S**
Hsu (45) Date of Patent: ** Jun. 4, 2019

(54) **CHESS SET**

(71) Applicant: **Carolyn Hsu**, San Francisco, CA (US)

(72) Inventor: **Carolyn Hsu**, San Francisco, CA (US)

(**) Term: **15 Years**

(21) Appl. No.: **29/629,561**

(22) Filed: **Dec. 14, 2017**

(51) LOC (11) Cl. **21-01**

(52) U.S. Cl.

USPC **D21/349**

(58) **Field of Classification Search**

(57) **CLAIM**

The ornamental design for a chess set, as shown and described.

DESCRIPTION

FIG. 1 is a top view of a chess set according to the present design; and,

FIG. 2 is a right, left, front, and rear side view, all of which are identical, thereof.

The underside of the chess set is flat and unornamented.

1 Claim, 2 Drawing Sheets
